MACHINE FOR AND METHOD OF HARDENING
CAMs

Stowell C. Wasson, Beauford E. Gavin, and Frank R. Pollard, Indianapolis, Ind., assignors to National Malleable and Steel Castings Company, Cleveland, Ohio, a corporation of Ohio

Application December 17, 1938, Serial No. 246,402

20 Claims. (Cl. 266—4)

This invention relates to a machine for hardening selected portions of articles, such as cam shafts, crank shafts and the like, in such a manner that the metallurgical structure of the remainder of the article does not change.

Our machine, in general, comprises a conveyor for the articles to be treated which grips the articles and carries them successively past various flame emitting burners, where they are heated to the proper temperature. Further movement of the conveyor carries the articles to other positions wherein a stream of fluid, such as air or water, is blown on the heated portion to quench and harden the selected portion. In articles such as cam shafts, the portions to be hardened are usually in various angled positions about the longitudinal axis of the member. A feature of our invention is the provision of novel means for rotating the article about its longitudinal axis as it passes along the conveyor so as to bring the portions to be hardened in proper relation to one of the burners.

An object of our invention is the provision, in a flame hardening machine, of means for automatically advancing the work through the conveyor, performing the various operations thereupon, and finally releasing the heat treated article. In this connection, we provide novel means for gripping the ends of the articles and other means for discharging the articles from the gripping device after the heat treatment is finished. In addition, we provide a novel mechanism for intermittently advancing the articles to position them for selected times beneath the burners.

Other objects and features of our invention will be best understood from consideration of the following description, taken in conjunction with the drawings, in which:

Figure 1 is a view in side elevation of a machine embodying our invention.

Figure 2 is a plan view of the machine shown in Fig. 1.

Figure 3 is a partial sectional view taken generally along the line 3—3 of Fig. 2, illustrating certain details of the invention.

Figure 4 is a partial sectional view along line 4—4 of Fig. 3.

Figure 5 is a partial vertical sectional view, taken along the line 5—5 of Fig. 1.

Figure 6 is a sectional view through one of the chucks.

Figure 7 is an end view of the chuck shown in Fig. 6.

Figure 8 is a partial sectional view taken gen-

erally along the line 8—8 of Fig. 3, showing one of the chucks in open position.

Figure 9 is a partial view showing a detail of a part of the conveyor.

5 Figure 10 is a plan view of the operating mechanism for the piston control valves.

Figure 11 is an isometric view of a part of the operating mechanism shown in Fig. 10.

10 Figure 12 is a view showing one of the types of articles that may be treated in our machine.

Figure 13 is an end view of the article shown in Fig. 12; and

15 Figure 14 is a diagrammatic view of the pistons and control valves showing the various connections therebetween.

Mounted on the framework of the machine generally designated by numeral 9, are pillow blocks 10 supporting a stationary shaft 11. A hollow shaft 12 is pivotally mounted on shaft 11, and at each end of shaft 12 there is rigidly secured a sprocket wheel 13, the latter and shaft 12 comprising the supporting structure for the conveyor. Secured to the inner side of each sprocket 13 are bosses 14 (Fig. 5), each of which 20 pivotally supports a hollow shaft 15. The bosses shown in the present application are equally spaced about sprocket 13, the desired spacing and the number required being determined by the number of cams or other surfaces on the article which it is desired to harden. On the inner ends of each shaft 15 is mounted a chuck 16 which comprises a base member 17 secured to shaft 15, and a pair of jaws 18 each pivoted on a pin 19. The jaws are shown in the form of bell-crank levers, one of the arms of each having a surface 20 for clamping the work-piece and another arm 21 operatively connected to a reciprocating element 22. In the present embodiment each of the arms 21 is adapted to enter a recess in member 22 so that movement of said member in one direction tends to pivot the jaws to open position, whereas movement in the opposite direction closes the jaws. Connected to member 22 and extending through shaft 15 is a jaw-operating rod 23. The outer end of each rod 23 is formed with a head 24. A compression spring 25 bears at one end against head 24 and at the other end against a spring seat 26. Head 24 and hence operating rod 23, are thus normally held in an outward position which rotates chuck jaws 18 toward each other, so as to clamp an object therebetween. Movement of head 24 and rod 23 to the left, as viewed in Fig. 8, rotates the jaws to open position. Secured to each shaft 15, as by a key 27, is a pinion 28 engaging an

30 article which it is desired to harden. On the inner ends of each shaft 15 is mounted a chuck 16 which comprises a base member 17 secured to shaft 15, and a pair of jaws 18 each pivoted on a pin 19. The jaws are shown in the form of bell-crank levers, one of the arms of each having a surface 20 for clamping the work-piece and another arm 21 operatively connected to a reciprocating element 22. In the present embodiment each of the arms 21 is adapted to enter a recess in member 22 so that movement of said member in one direction tends to pivot the jaws to open position, whereas movement in the opposite direction closes the jaws. Connected to member 22 and extending through shaft 15 is a jaw-operating rod 23. The outer end of each rod 23 is formed with a head 24. A compression spring 25 bears at one end against head 24 and at the other end against a spring seat 26. Head 24 and hence operating rod 23, are thus normally held in an outward position which rotates chuck jaws 18 toward each other, so as to clamp an object therebetween. Movement of head 24 and rod 23 to the left, as viewed in Fig. 8, rotates the jaws to open position. Secured to each shaft 15, as by a key 27, is a pinion 28 engaging an

internal gear 35 which is fixedly mounted in a framework 36 adjacent sprocket wheel 13.

It will be understood that each chuck assembly is the same as above described and likewise that the chucks on the opposite sprocket wheels are arranged in opposite pairs so that the article can be held transversely of the machine by a pair of chucks, one on each sprocket. Moreover, one internal gear 35 is mounted adjacent each sprocket. As the sprocket wheel is rotated in the manner to be later described, the pinions mesh with the teeth of the internal gears and rotate the chucks, each about its own longitudinal axis.

Mounted on the rear of frame 9 on a shaft 29 are sprocket wheels 37 operatively joined with sprockets 13 by chains 38. On the same shaft as sprockets 37 and secured to pivot therewith is a toothed element 39. Also on the shaft 29 is a freely rotatable member 40 having an arm 41 adapted to raise and lower pawl 42 into and out of engagement with teeth 43 on element 39. Rearwardly of sprocket 37 is a cylinder 44 provided with a piston 45 (see Fig. 14). Piston rod 46 extends outwardly of said cylinder and is joined with arm 41 of member 40 through a link 48. A pawl 49 pivoted to arm 41 is adapted to engage teeth 43 to rotate element 39 and hence sprocket 37 upon actuation thereof by the piston in cylinder 44.

Operation of the conveyor thus far described is as follows: Upon the admission of air to the right-hand side of cylinder 44, piston 45 moves to the left, as viewed in Fig. 1 or 14, causing pawl 49, through arm 41, link 48 and piston rod 46, to rotate element 39 and hence the sprocket 37 in a counter-clockwise direction. As this rotation occurs, arm 41 of member 40 permits the first adjacent tooth 43 to slip beneath pawl 42, but since arm 41 rotates with member 40, pawl 42 is permitted to drop and enter the space between the first and second adjacent teeth 43, thus forming a stop against further rotation of sprocket 37. Sprocket 37 thus moves one-sixth of a revolution, in the embodiment shown, upon each stroke of piston 45. However, since sprocket 37 is formed one-half the diameter of sprocket 13, the latter only moves one-twelfth of a revolution, thus rotating a given pair of chucks from the position illustrated at A (Fig. 1) to a position illustrated at B. The above described mechanism provides a simple and effective way of moving the articles to various positions and positively stopping them at a predetermined position in the machine.

The embodiment of the invention shown in the application is designed for hardening the cams on automobile cam shafts, one of which is shown in Figs. 12 and 13 of the drawings. This cam shaft is for a six-cylinder automobile and therefore has twelve cams arranged along the longitudinal extent of the shaft and assuming various angled positions about the circumference of the shaft. As shown in Fig. 13, the cams are arranged substantially in pairs about the shaft, each pair being spaced at an angle of 60 degrees from the pair immediately adjacent thereto. In each pair the two cams are offset at a slight angle to each other due to the fact that one operates an intake valve and the other operates an exhaust valve.

Mounted above framework 9 is a burner supporting framework 60. At the upper front end of this framework we provide tubes 61 and 62 upon which is slidably mounted the forward burner

carrier 63. Upon burner carrier 63 are mounted two pairs of burners 64, 65 and a single burner 66. As is clearly shown in Fig. 3, each burner is mounted on carrier 63 by means of a bracket 67 projecting into a boss 68 on the carrier and adjustably secured by means of a set-screw 69. The end of each bracket is formed with a hole, receiving a rod 70 extending transversely of the machine and the rod is adjustably secured in the bracket by set-screw 71. The other end of the rod is formed with a clamp 72 for securing the burner in position. Each burner comprises a pipe 73 connected to a source of fuel such as a combustible mixture of acetylene and oxygen, and at the opposite end, pipe 73 is divided, as at 74 and 75, so as to direct a flame on each side of the part of the cam to be hardened. Pipes 74 and 75 may be provided with suitable tips on the ends thereof, so as to direct the flame in the most efficient manner onto the cam. As shown in Fig. 2, each division 74 and 75 is formed of two pipes so that the flame from each burner is substantially the width of the cam; although, if desired, single pipes 74 and 75 may be used and provided with a multiple flame tip. By reason of the adjustable mounting of the burners on the burner carrier each burner may be positioned to direct its flame upon a cam and thus correct for the slight difference in the angular relation between the cams of each pair. Moreover, adjustments can be made to utilize the machine for cam shafts of different types. At the rear of frame 60 is a rear burner carrier 85 slidably mounted on hollow tubes 86 and 87. Pairs of burners 88, 89 and 90 and a single burner 84 are mounted on carrier 85 in the same manner as the burners on forward carrier 63.

At the front end of the machine is a loading carriage 91 having a platform 92 with notched ends 93. At the center of platform 92 is a block 94 having a semi-circular groove 95 in the top thereof. Adjacent block 94 is a block 96 having a recess 97 shaped to fit one of the cams. As can be seen in Fig. 3, recess 97 is at an angle so as to initially position the cam shaft such that as it passes through the machine the various cams will be rotated into proper relation with the burners. When the cam shaft is placed in carriage 91 with the shaft resting in grooves 93, cam b' (Fig. 4) in recess 97 and the shaft immediately adjacent the aforesaid cam in groove 95, the shaft may be pushed laterally until the lower portion of the cam b' in recess 97 engages the adjacent wall of block 94 directly below groove 95. In this manner correct positioning of the cam shaft laterally of carriage 91 is assured. At one side of carriage 91 are grooved wheels 98 which rest on a rail 99 of less width than the grooves in the wheels. On the opposite side of the carriage is a pair of wheels 100 having V-shape grooves 101 therein. These wheels rest upon a rail 102 having a shape corresponding to that of grooves 101 so that the carriage is positioned laterally of the machine.

Assuming a cam shaft first correctly positioned in carriage 91 and then clamped between a pair of chucks 16, rotation of sprocket wheels 13 in a counter-clockwise direction, as viewed in Fig. 3, will cause the cam shaft to rotate in the opposite or clockwise direction. Internal gears 35 have ten times as many teeth as pinions 28, and the latter in rotating once around gears 35 make nine complete revolutions about their own axes, one revolution being lost due to the fact that the pinions are themselves rotating in a circle. As each pinion is moved one-twelfth of the cir-

circumference of its internal gear at each stroke of the piston 45, it will rotate three-fourths of a revolution about its own axis in moving from one indexed position to the next. In Figs. 12 and 13 the various pairs of cams have been given similar reference letters so that they can be more readily identified. In Fig. 3 there are shown the various positions taken by the first cam *a'* of Fig. 12. It can be seen that this cam has rotated about its own axis three-fourths of a revolution in a clockwise direction between successive positions about the circumference of the conveyor. Cams *a*, *a'* being the first to be heated, are indexed beneath burners 64. As the conveyor moves in the machine, cams *b*, *b'* are heated by burners 65, cams *c*, *c'* by burners 66 and 84, cams *d*, *d'* by burners 88, cams *e*, *e'* by burners 89, and cams *f*, *f'* by burners 90.

The dot-dash lines of Fig. 3 show the positions of cam *a'* as it approaches and leaves a position wherein it is midway the tips at the ends of arms 74 and 75 of the burner. It will be observed that in approaching this position the point of the cam rotates easily into place without interfering with the tips of the burner. Likewise, in leaving the position it rotates in a clockwise direction so as to miss hitting the tip on arm 74. As will be later described, the indexing mechanism for shifting the cam from one position to another may be adjusted so as to permit the cam to remain beneath its burner for a sufficient time to raise the surfaces to be hardened to the desired temperature. After being heated the cam is moved to the next indexed position. At this location, that is, one-twelfth of a revolution in the present machine from the heating position, we have provided means for quenching the heated surfaces so as to obtain the desired hardened structure. A pipe 109 is secured to arm 74 of burner 64 and is bent at one end, as at 110, so as to direct a stream of fluid, such as air or water, against the heated surfaces of the cam. The other end of pipe 109 is connected to a source of fluid under pressure. After a given pair of cams is cooled, the cam shaft continues its movement through the machine and in each position one pair of cams is being heated and another pair cooled, in the manner described above, until all of the cams have progressed through the hardening cycle. In the last position of this cycle, as shown at C (Fig. 1), no heating takes place, inasmuch as the cams have already passed through six heating positions; thus there only remains the step of quenching the last pair of cams to be heated. When a cam shaft reaches position D (Fig. 3) the chuck jaws are automatically opened to release the shaft.

We provide means for opening the chuck jaws to insert the shafts in the following manner: Cylinders 111, one on each side of the machine, have pistons 112, the piston rods of which extend towards the center of the machine and may be formed with flat plates 113 on the ends thereof. These plates lie adjacent opposite pairs of chucks when the latter are in position for loading. Pistons 112 are pneumatically actuated and the air to the cylinders is controlled by a manually operated valve 114. Upon operation of the valve, air is admitted to the outer ends of cylinders 111 and the pistons are forced towards each other, causing plates 113 to force the chuck operating rods 23 inwardly to open the chuck jaws in the manner previously described. It will be observed from Fig. 2 that in the loading position the chuck jaws are vertical, that is, one

above the other, so that when they are opened, carrier 91 with its cam shaft in position for loading may be rolled so as to position the shaft between the open jaws of the chucks. Upon release of valve 114, pistons 112 are moved in the opposite direction and springs 25 expand and close the chuck jaws on the cam shaft.

Similar means is provided for releasing the cam shafts from the chucks after the hardening operation. Cylinders 115 are mounted on framework 9 on either side of the machine and are located opposite the ends of a cam shaft when the latter is in its lowermost position in the machine. Pistons 116 in said cylinders have piston rods extending towards each other and may be provided with flaring centering cups 117 adapted to engage the heads 24 of a pair of oppositely disposed chuck operating rods. When pistons 116 are forced towards each other by the entry of air in the outer ends of cylinders 115, a pair of the chucks are opened and the cam shaft held thereby is discharged from the machine. The cups 117 may be flared, as shown in Figs. 5 and 8, so that upon engagement therewith with heads 24 the flaring walls 118 serve to correctly position the sprocket wheels 19 in such a manner that the pair of chucks to be next loaded will be in proper relation to the loading carriage. The flaring walls 118 on cap 117 may not be necessary in all cases, inasmuch as the pawls 42 and 49 of the indexing mechanism should of themselves locate the chucks in the proper relation to the burners and loading carriage.

In some instances it may be necessary to move the burners closer to the cams than is shown, and in such cases the burners would interfere with the cams when the cam shafts are moved from one position to another. To avoid this interference we provide means for shifting the burner carrier laterally of the machine so as to position the burners to one side or the other of the cams. As has been previously stated, burner carriers 63 and 85 are slidably mounted on tubes 61 and 62, and 86 and 87, respectively. At one side of the machine is a cylinder 120 having a piston 121 and piston rod 122, the latter being connected to burner carrier 85 through a bracket 123. The piston is pneumatically actuated to shift burner carrier 85 laterally of the machine, and burners 84, 88, 89 and 90 are moved to positions between certain of the cams. Cylinder 124, on the opposite side of the machine from cylinder 120, has a piston 125 and piston rod 126 connected to a bracket 127 on carrier 63 to move the latter, and hence burners 64, 65 and 66, laterally of the machine to positions between certain others of the cams. Stop collars 128 are provided to limit movement of the burner carriers. The burner carriers are shown as being shiftable in opposite directions for the reason that the cam shaft illustrated herein has bearing portions *g*, *h* and *i* and gear *j* which necessitates movement of adjacent burners away from said portions to clear the associated cams. For instance, cam *a'* (Fig. 12) is adjacent bearing *i* so the burner 64 that heats cam *a'* moves from the full line position to the position shown in dot-dash lines.

To prevent overheating of the metal between cams, we provide a series of pipes 129, one on each side of each of the burners which direct streams of water on the cam shafts adjacent the cams being heated so as to dissipate the heat reaching these portions by conduction.

In Figs. 10 and 11 there is shown the timing

mechanism for operating the valves controlling the indexing, unloading and burner shifting cylinders and the air or water quench. The mechanism is mounted on the main frame of the machine beneath the loading station, as shown in Fig. 1. (To avoid confusion the timing mechanism is not shown in Fig. 2.) Secured to shaft 130 are cams 131, 132, 133 and 134 for operating respectively air quench valve 135, indexing valve 136, unloading valve 137 and burner shifter valve 138. Shaft 130 is rotated, through a speed reducer, by a motor 139 and belt 140. Each valve has a bell-crank lever 141 pivotally mounted on the top thereof provided with a roller 142 adapted to be engaged by the respective cams for rocking each lever about its pivot. Valves 136, 137 and 138 are four-way valves of standard make and each has a pair of plungers 143 (Fig. 14) adapted to slide on members 144 for controlling the direction of air flow into double acting cylinders 44, 115 and 120. Each plunger 143 is formed with an internal groove so as to provide an air chamber 145 between the plunger and member 144. When a plunger is in lowermost position, the air chamber 145 spans ports 146 and 147 in member 144 permitting air to pass from air supply line 148 through the valve to one end of a cylinder. When a plunger is in its upper position, the lower port 146 is open to the atmosphere and permits air to be exhausted from a cylinder.

Each of bell-crank levers 141 on valves 136, 137 and 138 has a pair of arms 150 connected by rods 151 to the plungers of the valve, thus when one plunger 143 in a given valve is up the other plunger is down. A spring 152 between one of the plungers and top wall 153 of each valve normally maintains the plungers in such position as to hold the pistons in the respective cylinders in retracted position. Valve 114, which controls the loading cylinder, is the same as the valves just described except it is manually operated. Valve 135 has only one plunger since its purpose is to control the air or water supply used for cooling the heated cams on the cam shaft being treated. Pipe 154, leading from valve 135, is joined with pipes 109 which direct the cooling fluid (air in the present instance) against the heated surfaces of the cams.

The operating of the timing mechanism is as follows: Assuming the machine loaded with cam shafts between each pair of chucks in the first nine positions of the conveyor starting with the loading station, cam 134 of the timing device operates valve 138 admitting air into the outer ends of cylinders 120 and 124 to shift the burner carriers and holds the latter in shifted position until indexing cam 132 operates valve 136 to actuate piston 45 and move the conveyor to its next position. Cam 134 then releases valve 138 and air is admitted to the inner ends of cylinders 120 and 124 shifting the burner carriers to their normal positions, whereupon the cams of the articles being treated are heated by flames from the various burners. Immediately after the conveyor has been moved to a new position, cam 133 of the timing device operates valve 137 actuating pistons 116 and opening the pair of chucks at the unloading station. It will be observed that cam 133 holds valve 137 in chuck opening position and maintains cups 117 in engagement with heads 24 substantially all the time the heating operation is taking place, thus effectively precluding the conveyor from shifting during this portion of the cycle. Shortly

after the conveyor has moved to a new position (in the order of two to five seconds), cam 131 opens valve 135 causing an air blast to pass through pipes 109 which cools the surfaces of the cams heated in the previous position of the conveyor. The time interval of from approximately two to five seconds is to permit the heat to penetrate into the cam and obtain a substantial thickness of hard metal.

We prefer to adjust the speed of the timing shaft 130 so that the period the cams are heated is about fifteen seconds. However, since the speed of the timing mechanism must be correlated with the temperature of the burner flame the two may be varied at will so as to obtain the desired hardness of cam surface. Moreover, cam 131 may be shifted on shaft 130 to turn on the cooling air sooner or later than herein indicated so as to change the characteristics of the metal being treated.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

What we claim is:

30 1. In a method of tempering metallic articles consisting of causing a succession of said articles to travel along a predetermined path with a regularly intermittent motion with periods of rest between the steps of said motion during which periods said articles are held stationary, rotating said articles between points of rest in said intermittent motion to move selected portions thereof to predetermined positions, successively exposing said selected portions of each article to the heating effect of a high temperature flame during said periods of rest and when in said predetermined positions and quenching said articles.

45 2. In a method of tempering metallic articles consisting of causing a succession of said articles to travel along a predetermined path with a regularly intermittent motion with periods of rest between the steps of said motion during which periods said articles are held stationary, rotating said articles between points of rest in said intermittent motion to move selected portions thereof to predetermined positions, successively exposing said selected portions of said articles to the heating effect of a high temperature flame at one position of rest and when in said predetermined positions and thereafter quenching at the next position of rest of said articles.

60 3. In a method of tempering metallic articles consisting of causing a succession of said articles to travel along a predetermined path with a regularly intermittent motion with periods of rest between the steps of said motion during which periods said articles are held stationary, rotating said articles between points of rest in said intermittent motion to move selected portions thereof to predetermined positions, successively exposing said selected portions of said articles to the heating effect of a high temperature flame at one position of rest and when in said predetermined positions, thereafter quenching at the next position of rest of said articles, and releasing each article after all of said selected portions thereof have been heated and quenched.

75 4. In a flame hardening machine, means for

intermittently moving articles to be hardened through the machine and for holding said articles stationary during periods of rest in said movement, means for rotating said articles each about its own axis, only during said movement, means directing a high temperature flame on selected portions only of said articles during periods of rest and means for quenching the heated selected portions of said articles.

5. In a flame hardening machine, an intermittently movable conveyor, said conveyor being adapted to receive articles to be hardened, means for rotating said articles only during said intermittent movement of the conveyor, means directing a high temperature flame on selected portions only of said articles for a predetermined interval during a period of rest in said intermittent movement, and means for quenching the heated selected portions of said articles after a predetermined time from the end of said interval.

6. In a machine for hardening cam shafts having a plurality of cams disposed in angular relation about the shaft, comprising a plurality of flame emitting burners, means for moving the cam shafts into positions to be heated by said burners, means for arresting movement of the cam shafts for a predetermined interval in each of said positions, and means for rotating said cam shafts between successive positions to bring various ones of the cams into heating relation to the burners.

7. In a machine for hardening selected portions only of articles wherein the selected portions are disposed in various angled positions about the article, comprising a conveyor for the articles, means associated with said conveyor for rotating the articles each about its own axis only while traveling with said conveyor to bring said portions to predetermined stationary positions in said machine, a plurality of flame emitting burners adjacent said conveyor placed in heating relation to said portions, and means for arresting movement of said conveyor for predetermined intervals when said selected portions are in heating relation to said burners.

8. In a machine for hardening selected portions only of articles wherein the selected portions are disposed in various angled positions about the article, comprising a conveyor for the articles, means associated with said conveyor for rotating the articles each about its own axis only while traveling with said conveyor to bring said portions to predetermined stationary positions in said machine, a plurality of flame emitting burners adjacent said conveyor placed in heating relation to said portions, means for arresting movement of said conveyor for predetermined intervals when said selected portions are in heating relation to said burners, and means for quenching said selected portions after being heated.

9. In a machine for hardening cams on cam shafts, a conveyor for intermittently moving the shafts through the machine, a plurality of burners positioned in heating relation to the cams on said shafts at points of rest in said intermittent movement, means for rotating the shafts only between successive points of rest to bring various cams thereon into fixed heating relation to the burners, and means for quenching the heated portions of the shafts.

10. In a machine for hardening protruding cams on cam shafts, comprising an intermittently moving conveyor for said shafts, a plurality of

burners spaced about said conveyor, each burner being positioned so as to be in heating relation to one of the cams on a shaft during a period of rest in said intermittent movement, means for rotating said shafts each about its own axis only while moving from one position of rest to the next succeeding position of rest, and means for shifting said burners out of heating relation to the cams during movement of the conveyor between successive positions of rest.

11. In a machine for hardening protruding cams on cam shafts, comprising an intermittently moving conveyor for said shafts, a plurality of burners spaced about said conveyor, each burner being positioned so as to be in heating relation to one of the cams on a shaft during a period of rest in said intermittent movement, means for rotating said shafts each about its own axis only while moving from one position of rest to the next succeeding position of rest, and means for shifting said burners out of heating relation to the cams during movement of the conveyor between successive positions of rest.

12. In a machine for hardening protruding cams on cam shafts, comprising an intermittently moving conveyor for said shafts, a plurality of burners spaced about said conveyor, each burner being positioned so as to be in heating relation to one of the cams on a shaft during a period of rest in said intermittent movement, means for rotating said shafts each about its own axis only while moving from one position of rest to the next succeeding position of rest, and means for shifting said burners out of heating relation to the cams during movement of the conveyor between successive positions of rest, and means for quenching said heated cams.

13. In a machine for hardening machine comprising a conveyor, means for intermittently moving said conveyor, pivotally mounted clamping means on said conveyor for holding the articles to be hardened, an internal gear adjacent said conveyor and a pinion on said clamping means engaging said gear for rotating said means only upon movement of said conveyor, and a plurality of flame emitting burners positioned about said conveyor so as to be in heating relation to the articles to be hardened during periods of rest in said intermittent movement.

14. In a machine for hardening cams on cam shafts, an intermittently moving conveyor adapted to receive the cam shafts, means for rotating said shafts each about its own axis only during movement of said conveyor, a plurality of burners positioned so as to be in heating relation to the cams on the shafts during periods of rest in said intermittent movement, a platform for loading the shafts in the machine, and means on said platform for initially positioning the cam shafts in proper relation to the conveyor.

15. In a flame hardening machine, an intermittently moving conveyor for the articles to be hardened, means for rotating said articles only during said movement, means directing a high temperature flame on selected portions of said articles during a period of rest in said intermittent movement, means for quenching the heated portions of said articles, and timing means for causing operation of said conveyor and quenching means.

16. In a machine for hardening protruding cams on cam shafts, comprising an intermittently mov-

ing conveyor for said shafts, a plurality of burners spaced about said conveyor, each burner being positioned so as to be in heating relation to one of the cams on a shaft during a period of rest in said intermittent movement, means for rotating said shafts each about its own axis only while moving from one position of rest to the next succeeding position of rest, means for shifting said burners out of heating relation to the cams during movement of the conveyor between successive positions of rest, and timing means for causing operation of said conveyor and shifting means.

17. In a flame hardening machine, a plurality of flame emitting burners spaced about said machine, a conveyor successively moving articles into and out of the zones of said flames, means for rotating said articles each about its own axis during said movement and for stopping rotation of said articles during periods of rest in said movement so as to bring selected portions of said articles in the zones of said flames, and means for quenching said selected portions after passing out of said zones.

18. In a flame hardening machine, a conveyor comprising a pair of oppositely disposed rotating elements, gripping means on said elements for holding the articles to be hardened, means for intermittently moving said conveyor, a burner, means for rotating said gripping means during said movement to bring said articles to predetermined stationary positions in said machine and for stopping rotation of said article when in said stationary positions, said burner being adapted to direct a high temperature flame on selected surfaces of said articles when the latter are in said stationary positions.

19. In a flame hardening machine, a conveyor comprising a pair of oppositely disposed rotating elements, gripping means on said elements for

holding the articles to be hardened, means for intermittently moving said conveyor to bring said articles to predetermined stationary positions in said machine, a burner, means for rotating said gripping means during said intermittent movement and for stopping said rotation when the articles are in said predetermined stationary positions so as to position selected surfaces of said articles in heating relation to said burner, said burner being adapted to direct a high temperature flame on the selected surfaces of the articles to be hardened during periods of rest in said intermittent movement, and means for quenching said selected surfaces after a predetermined interval from said heating period.

20. In a flame hardening machine, a conveyor comprising a pair of oppositely disposed rotating elements, gripping means on said elements for holding the articles to be hardened, means for intermittently moving said conveyor to bring said articles to predetermined stationary positions in said machine, a burner, means for rotating said gripping means during said intermittent movement and for stopping said rotation when the articles are in said predetermined stationary positions so as to position selected surfaces of said articles in heating relation to said burner, said burner being adapted to direct a high temperature flame on the selected surfaces of the articles to be hardened during periods of rest in said intermittent movement, means for quenching said selected surfaces after a predetermined interval from said heating period, and means for releasing said articles from said gripping means after being quenched.
